ELECTRICAL CONNECTION FOR ELECTRIC SIGNS

Harry L. Kresge, New York, N. Y.

Application February 2, 1937, Serial No. 123,612

1 Claim. (Cl. 173—328)

This invention relates to new and useful improvements in electric signs and more particularly it relates to so-called electrode connections for neon signs. One type of electrode connector for such signs, in more or less general use is known as a bushing, and it is this type to which the present invention relates.

It is one object of the invention so to construct the device that the possibility of short circuiting will be practically eliminated.

Another object of the invention resides in a new and novel construction whereby lodgment of foreign bodies such for example as insects and a consequent short circuiting of the sign is eliminated.

Because of the fact that the electrodes of signs of the neon type are not of uniform length, it is necessary to employ an electrical connection between the source of supply and the electrode, which connection is of a flexible nature and it is a further object of the present invention to provide a new and novel construction whereby a good electrical connection between the source of supply and the electrode of the sign is assured.

Other features of the invention relate to certain novel and improved constructions, arrangements and combinations of parts hereinafter described and particularly pointed out in the claim, the advantages of which will be readily understood and appreciated by those skilled in the art.

The invention will be understood from the accompanying drawing illustrating the invention in its preferred forms and the following detailed description of the construction therein shown.

In the drawing:

Figure 1 is a perspective view illustrating a device constructed in accordance with one form of the present invention, and

Figure 2 is a view thereof, partly in elevation and partly in longitudinal section.

In that form of the invention illustrated in Figures 1 and 2, the bushing comprises a hollow cylindrical member 10 having the usual enlarged portion or flange 11. The opposite end of the body portion is chamfered or cut away as at 12 to provide a shed for moisture or the like. Projecting from the periphery of the end of the main body portion 10 there is an arm 13 which is rigid in character and said arm has its free end spaced an appreciable distance from the adjacent end of the main body portion 10. The cylindrical body is made of porcelain or other suitable non-conducting material and the arm 13 is preferably formed as an integral portion thereof.

Secured to the end of the arm and preferably depending therefrom there is a second arm 14. This arm may be secured in position upon the arm 13 by providing a right angular portion 15 through which a bolt 16 passes, the bolt 16 also passing through an opening 17 in the end of the arm 13. Secured to the lower end of the arm 14 by means of a screw or the like 18 there is a conventional clip 19. Also secured to the arm 14 and extending in the direction of the main body portion 10 there is a conductor 20. This conductor 20 is of a flexible nature and comprises a coil spring of resilient material. One end of this conductor is passed around the bolt 18, thus providing means for electrically connecting this conductor 20 to the arm 14, which also serves together with the bolt 18 to electrically connect the clip 19 with the conductor 20. The reference numeral 21 designates a terminal which is preferably of the type illustrated in my co-pending application, Serial Number 83,099, filed May 29, 1936, for Electrode terminal, and this terminal is adapted to embrace the free end 22 of the electrode of the neon sign and has electrical contact therewith.

Because of the fact that the flexible conductor 20 has a tendency to sag, it often happens that the electrical connection between the terminal 21 and the electrode 22 becomes broken or imperfect, and it is the object of the present invention to prevent this sagging of the conductor 20, thus insuring a good electrical contact between the terminal 21 and the electrode 22 at all times.

In that form of the invention illustrated in Figures 1 and 2 this result is accomplished by supporting the inner end of the flexible conductor 20 from the rigid arm 13 by passing a portion of said conductor about or around said arm 13. This construction is shown in Figures 1 and 2 in which the end convolution 25 of the coiled flexible conductor 20 is passed around the arm 13, as illustrated at 26 in said figures. While I have shown but one of the convolutions of the coiled conductor 20 as passed around the arm 13, two or even more may be so constructed, this being immaterial in so long as the proper support for the conductor 20 is had.

By this construction it will be apparent that the flexible conductor 20 is free to function in the ordinary manner since the support thereof from the arm 13 is of such nature that that part of the conductor which embraces the arm 13 is free to slide therealong, thus permitting the structure to accommodate itself to various lengths of the electrode. It will also be apparent

that the conductor 20 is, by the construction illustrated, supported in axial alinement with the axis of the main body portion of the bushing, thus insuring good electrical contact between 5 the terminal 21 and the electrode of the sign.

By the construction employed in the bushing, it is obvious that insects which might come in contact with either the conductor 20 or the terminals of the devices will, upon being killed 10 by reason of the electric current therein, not lodge or be collected in such a manner as to cause a short circuiting of the sign, but will instead fall directly away from the electrical connections and thus be disposed of.

15 From the foregoing it is apparent that the present invention provides a new and improved bushing construction and arrangement for neon signs in which the objects are efficiently accomplished, and while the invention has been 20 disclosed in its preferred forms it is to be understood that it is not to be limited to the specific constructions shown but may be illustrated in

other forms without departing from the spirit and scope thereof.

Having thus described the invention, what is claimed as new, is:

A bushing for illuminated electric signs comprising a hollow cylindrical body, a rigid arm extending from one end of said hollow cylindrical body and having its free end spaced an appreciable distance from the body portion, an electrical contact member carried by said arm 10 adjacent its free end, and a flexible electrical conductor connected at one end to the electrical contact member and having its other end free for attachment to an electric sign electrode, said electrical conductor comprising a coiled member 15 suspended at its inner end by passing at least one of its convolutions around said rigid arm to suspend the coiled conductor therefrom in alinement therewith and in alinement with the axis of the hollow cylindrical bushing. 20

HARRY L. KRESGE.
